PENNSYLVANIA.

CIRCULAR INDEPENDENT-NEEDLE KNITTING-MACHINE.

No. 857,836.

Specification of Letters Patent.

Patented June 25, 1907.

Application filed July 25, 1906. Serial No. 327,619.

To all whom it may concern:

Be it known that I, CHARLES A. SANTMYERS, a citizen of the United States, residing at Philadelphia, county of Philadelphia, 5 and State of Pennsylvania, have invented a new and useful Improvement in Circular Independent-Needle Knitting-Machines, of which the following is a full, clear, and exact description, reference being had to the accompanying drawings, which form a part of this specification.

The object of my invention is to so construct a knitting machine that, at any point in the fabric, one or more needles may be moved out of action and its stitch dropped to form an open-work or drop stitch effect, and at any other point in the fabric, said needle or needles may be returned into action and take the thread.

The invention is particularly useful in the manufacture of stockings, either of the drop stitch or open work type, or of the combined drop stitch and tuck-stitch type, otherwise known as lace-work. In stockings of this character, it is essential that there should be no drop-stitching in the heel, toe or lower part of the foot. It is also highly desirable that there should be no drop-stitching in the upper part of the leg, particularly in ladies' and children's stockings.

My invention consists in an attachment designed to be applied to knitting machines of the circular type by which the above-stated object is effected.

The invention is illustrated, and herein-after described, as applied to a known type of circular independent needle knitting machine adapted to the manufacture of circular work only, although it will be understood that the invention is not limited in its application to any particular type of such machine.

The machine is not shown or described in its entirety but only so much thereof as is necessary to a full understanding of the invention.

In the drawings: Figure 1 is a plan view of a segment of the rotatable cam-cylinder and the actuating mechanism for certain of the cams; Fig. 2 is a side-elevation of the same showing the cams in dotted lines, the view, however, being developed for purposes of clearness; Fig. 3 is a view, similar to Fig.

2, showing the movable cams in their other positions and with the actuating mechanism omitted; Fig. 4 is a side elevation, partly in section of the part of the machine embodying my invention; Figs. 5 and 6 are sectional views showing the operation of the needle guard and deflecting cam upon the drop- 60 stitch needles; Fig. 7 is a comparative view of the three sets of needles; Fig. 8 is a developed view showing all the cams.

10 is the housing, 100 the knitting head to which is secured the stationary needle cylinder 11, 12 the cam ring rotatable on the knitting head, 13 one of the segments of the cam-cylinder secured to the cam-ring, 14 a rack on the cam-ring, 15 the beveled pinion engaging and operating the rack, 16 the pattern-wheel, 17 a lever adapted to be lifted by the pattern wheel, 18 a plunger adapted to be lifted by the lever 17, 19 a disk on the plunger by which the levers for operating the movable cams are operated.

It will be understood that the pinion 15 is driven from the main driving shaft, by which a continuous rotation is imparted to the cam-cylinder. It will also be understood that the pattern wheel 16 is also driven from the main driving shaft, and its rotation governed and controlled by driving and governing mechanism well known in the art, but not herein shown, and not necessary to be described for the purpose of understanding my invention.

The particular style of machine to which I have applied my invention is of the two-feed type provided with lace-work attachment. Such a machine, as heretofore constructed, is provided with two cam segments, carrying respectively needle-lifting cams corresponding to cams 30 and 30^a, stitch cams, corresponding to cams 21 and 21^a, beyond the needle-lifting cams respectively, and guide cams 22 and 22^a, the needle lifting cam raising a needle to raise a latch above the previously formed loop and bring the hook above the thread fed from the thread carrier, and the stitch cam depressing the needle to cause the hook to engage said thread and draw it down through, and cast off, said loop, and form a new loop. The cams of the two segments are exact duplicates except that one of the needle lifting cams raises the needles to a higher level than the other.

The regular needles 50, however, are raised by both of the needle lifting cams a distance sufficient to draw the loops down over their latches as before described, but the tuck-stitch needles 51, being provided with longer latches than the regular needles, will not be elevated by the lower of said cams a sufficient distance to permit the loops carried thereby to clear their latches, and consequently each 10 of said needles will retain its loop, and elongate it while drawing down the new thread engaged by its hook to form a crossing loop. The higher of the two needle-lifting cams, however, raises the tuck-stitch needle sufficiently 15 high to raise its latch above the two loops carried by it, and thereafter, when a tuck-stitch needle is again depressed by the action of the adjacent stitch cam, the thread caught by the hook will be drawn down 20 through, and cast off, both the elongated loop and crossing loop, and form a new loop. The lower of said needle-lifting cams may be designated, therefore, the lacing cam, and the new cams forming part of my invention 25 are preferably applied to the segment that carries the lacing cam. The cam 30, in the position illustrated in Fig. 3, represents the lacing cam as heretofore constructed and operating as described.

30 In my invention instead of omitting one or more needles on each side of a tuck-stitch needle, needles 52 (which I shall designate hereinafter the drop-stitch needles) are provided. When it is desired to move these 35 needles out of action, these needles, after passing the stitch cam 21 in advance of the lacing cam 30, are caused to cast their loops and be drawn down out of action and to be held out of action until it is desired to 40 again bring them into action. For this purpose I have provided the following means, which are to be considered as merely preferable so far as the embodiment of my invention is concerned. The drop-stitch needles 45 are formed with longer butts than the other needles, and with shorter latches than the regular needles. By means of a clearing cam 23, which is shown as integral with the guide cam 22, all the needles are raised but only 50 the drop-stitch needles are raised to a height sufficient to elevate their latches above their loops. 40 is a deflecting cam which is not sufficiently thick to engage the short butts of the regular and tuck-stitch needles, 55 but which is of sufficient thickness to engage the long butts of the drop stitch needles. This cam (when depressed) deflects the drop-stitch needles downwardly and brings them under the action of a withdrawing cam 24, 60 which is formed by cutting a cam-way in that part of the guide-cam 22 beyond the clearing cam 23. During the downward movement of the tuck-stitch needles, the loops carried thereby slip over the closed 65 latches of the needles and are thus cast off.

Thereafter, the drop-stitch needles remain in their lowered inoperative position until such time as it is desired to bring them into action, at which time a reinstating cam 31 is moved upwardly, and the drop-stitch 70 needles are deflected thereby to bring them under the action of the guide cam, which restores them to operative position. Previously to the elevation of the cam 31, the deflecting cam 40 has been raised, so that it 75 will be ineffective to deflect the drop-stitch needles to the cam 24. Thereafter, the drop-stitch needles will operate as regular needles.

It will be understood that in passing from lace knitting to plain knitting, not only is it 80 necessary for the drop-stitch needles to be moved into operation, but it is also necessary (or at least desirable) to cause the tuck-stitch needles to knit as regular needles. This latter result is effected by raising the 85 lacing cam 30 to a height sufficient to lift the tuck-stitch needles, as well as the regular needles, a distance sufficient to cause the latches of the tuck-stitch needles to clear the loops carried by such needles. 90

Having described the action of the various cams, the mechanism whereby their operation is rendered automatic will now be described.

32, 33, are pins, both of which are secured 95 to the lacing cam 30 and the first of which is also secured to the reinstating cam 31.

34 is a spring seated in the cam-segment and engaging, and normally upholding, a pin 35, which is fixedly connected with the pin 100 33 by means of the yoke arm 335.

36 is an arm secured to the pin 35 and having a beveled upper face.

37 is a lever secured to the upper end of an upright shaft 39 and having a pin 38 engaging 105 the arm 36. When said shaft is turned so as to move the lever 37 inwardly, the pin thereon slides inwardly along the beveled face of the arm 36 and depresses the pin 35, thereby also depressing the pins 32 and 33 110 and cams 30 and 31. The upright shaft 39 turns in bearings in the cam segment and is geared to another upright shaft 380, also turning in bearings in the cam segment, by means of the gears 391 and 381 respectively 115 on the shafts 39 and 380.

392 is a lever secured to the shaft 39. 382 is a lever secured to the shaft 380. Each of these levers is adapted to be actuated by the disk 19 on the plunger 18. When 120 the disk 19 strikes the lever 382, the shaft 380 is turned, which, through the gears 381 and 391, turns the shaft 39 so as to depress the cams 30 and 31 as before described. When the disk 19 strikes the lever 392, the 125 shaft 39 is turned so as to move the lever 37 outwardly, and permit the spring 34 to elevate the cams 30 and 31. It will be understood that when one of the levers 392 or 382 is moved inwardly, the other is moved out- 130

wardly in position to be struck by the disk 19, but as the two levers are at different levels, the outwardly extending lever will not be struck by the disk until the latter is raised or lowered into appropriate position.

The raising and lowering of the disk 19 and plunger 18 is effected by the lever 17, whose position is in turn controlled by the pattern wheel 16. The pattern wheel is provided with detachable segmental teeth which, as the wheel revolves, engage the lever 17, and raise it or hold it stationary or permit it to drop. The teeth 160 of the pattern wheel are of such height that the lever 17 and plunger 18 are raised or held thereby in such position that in the rotation of the cam, the levers 382 and 392 pass respectively above and below the disk 19. When, however, the tooth 383, which is higher than teeth 160, underrides the lever 17, the plunger 18 and disk 19 are elevated into position to strike the lever 382 and depress the cams 30 and 31. The cams remain depressed until the tooth 393, which is lower than teeth 160, underrides the lever 17, when said lever, and the plunger 18 and disk 19, drop into such position that the lever 392 is struck by the disk 19, causing the cams 30 and 31 to be raised.

30 The deflecting cam 40 is secured to the pin 41 which is seated on the spring 42, by which the cam 40 is normally held in its upper, or inoperative, position. Secured to the pin 41 is a head 43 having a beveled upper face.

35 44, 45 46 is a three armed lever pivoted between its ends on the cam segment, and carrying on its end 44 the pin 47 adapted, when the lever swings in one direction, to move over the beveled face of the arm 43 and depress the pin 41 and the cam 40 carried thereby. When the arm 45 is struck by the disk 19, the arm 44 of the lever is moved into position to depress the cam 40. At the same time the arm 46 of the lever is moved outwardly into position to be struck by the disk 19. When the disk 19 strikes the arm 46 of the lever, the arm 44 of the lever is moved outwardly, permitting the spring 42 to lift the cam 40. At the same time the arm 45 is moved outwardly into position to be struck by the disk 19. It will be understood that when the arm 45 of the lever is moved inwardly by the disk 19, the arm 46 of the lever is moved outwardly into position to be struck by the disk, and vice versa, but as 45 and 46 are at different levels, the outwardly extending member will not be struck by the disk until the latter is raised or lowered into appropriate position.

60 The raising and lowering of the disk 19 into position to strike one or the other of the actuating arms 45, 46, is governed by the teeth 450 and 460 respectively of the pattern wheel. When the tooth 450 underrides the lever 17, the latter raises the plunger 18 and

disk 19 into such position that the disk 19, in the succeeding revolution of the cam cylinder, strikes the arm 45, thus effecting the lowering of the cam 40. The cam remains depressed until the tooth 460 underrides the lever 17, when the plunger 18 and disk 19 are raised into such position that the disk 19, in the succeeding revolution of the cam cylinder, strikes the arm 46, causing the cam 40 to be raised. Let it be assumed that the needles are on plain knitting, at which times the cams 30 and 31 and the cam 40 are elevated, as before described, and as shown in Fig. 2, and are about to pass to lace-work. At this time the tooth 383 underrides lever 17, raising the disk 19 into position to strike the lever 382, thereby causing the cams 30 and 31 to be depressed, as shown in Fig. 3. Thereafter the cam 30 acts as a lacing cam, that is, it does not elevate the tuck-stitch needles sufficiently to move their latches above the loops. Immediately thereafter the tooth 450 underrides lever 17, raising disk 19 into position to strike the arm 45, thereby causing the cam 40 to be depressed, as shown in Fig. 3, and deflect the drop-stitch needles to cam 24 which withdraws them from action. The cam 31 has moved downward with the cam 30, so that it is in its inoperative position and the drop stitch needles remain inoperative during the formation of lace-work.

At any time before the return to plain knitting, the teeth 384 and 451 (corresponding in elevation to teeth 383 and 450 respectively) successively underride the lever 17, and lift the disk 19 which, however, does not strike lever 382 or arm 45, as the same have already been moved in. When the next tooth 460 underrides the lever 17, the disk 19 is raised into position to strike the arm 46, thereby causing cam 40 to be raised. When, the needles are about to return to plain knitting, the tooth 393 underrides the lever 17, the disk 19 drops into position to strike the lever 392, thereby causing cams 30 and 31 to be raised. The cam 30 then ceases to act upon the tuck-stitch needles as a lacing cam, but lifts the same sufficiently high to draw their latches above their loops, thus causing the tuck-stitch needles to do plain knitting. The cam 31, being raised, moves the drop-stitch needles into action.

To insure the opening of the latches of the drop-stitch needles while being moved into operative position by the cams 31 and 22, a brush 60 is provided, which engages any closed or partly open latches and opens them fully. The guard 62, secured to the thread guide 61, holds the latches of the needles open until the needles are moved down by the stitch cam 30. When, however, the drop-stitch needles are acted upon by the depressed deflecting cam 40, they are lowered so that their latches are below the influence

of the guard 62, the latter being notched, as at 63, to permit the latches to close and allow the thread to be cast off, as before described (see Fig. 5). When, however, the deflecting

5 cam 40 is raised, the drop-stitch needles are not drawn down by the cam a distance sufficient to enable the latches to close (see Fig. 6.)

Having now fully described my invention, what I claim and desire to protect by Letters

10 Patent is:

1. In a knitting machine, the combination with the knitting cylinder and the regular, tuck-stitch and drop-stitch needles, of the cam cylinder, the lace cam adapted when elevated, but not when depressed, to lift the tuck stitch needles a distance sufficient to cause their latches to clear their loops, the stitch cam, the clearing cam adapted to lift the drop stitch needles to cause their latches to clear 15 their loops, cam devices adapted to thereafter withdraw said needles from action, a reinstating cam adapted to restore the needles thus rendered inactive into working position, means to render said cam devices inoperative 20 to withdraw said needles, and means to depress the lace cam and to move said reinstating cam into inoperative position.

2. In a knitting machine, the combination with the knitting cylinder and the regular, tuck-stitch and drop-stitch needles, of the cam cylinder, the lace cam adapted when elevated, but not when depressed, to lift the tuck-stitch needles a distance sufficient to cause their latches to clear their loops, the 30 stitch cam, the clearing cam adapted to lift the drop stitch needles to cause their latches to clear their loops, the withdrawal cam, the deflecting cam adapted when depressed to engage the drop-stitch needles and move 35 them into position to be acted upon by the withdrawal cam, the reinstating cam adapted when elevated to be moved into position to be engaged by the inactive drop-stitch needles and restore the latter to operative position, and means to elevate and depress the 40 lace cam, reinstating cam and deflecting cam.

3. In a knitting machine, the combination with the knitting cylinder and the regular needles, the tuck-stitch needles having long 45 latches and the drop stitch needles having short latches and long butts, of the cam cylinder, the lace cam adapted to elevate all the needles but when depressed to lift the tuck-stitch needles a distance insufficient to cause 50 their latches to clear their loops, the stitch cam, the clearing cam adapted to lift the drop-stitch needles to cause their latches to clear their loops, the withdrawal cam, the deflecting cam adapted when depressed to engage 55 the long butts of the drop-stitch needles and move them into position to be acted upon by the withdrawal cam, the reinstating cam adapted when elevated to be moved into 60 position to be engaged by the inactive drop-stitch needles and restore the latter to op-

erative position, and means to elevate and depress the lace cam, reinstating cam and deflecting cam.

4. In a knitting machine, the combination with the knitting cylinder and the regular needles, the tuck-stitch needles having long latches, and the drop-stitch needles having short latches and long butts, of the cam cylinder, the lace cam adapted to elevate all the needles, means to depress the lace cam thereby causing it to lift the tuck stitch needles a distance less than that required to cause their latches to clear their loops, the stitch cam in advance of the lace cam, the guide cam in advance of the stitch cam, the clearing cam adapted to lift the drop-stitch needles to cause their latches to clear their loops, the deflecting cam adapted to engage the long butts of the drop-stitch needles, the withdrawal cam, means to depress the deflecting cam in line with the withdrawal cam, thereby causing the drop-stitch needles to be withdrawn from operation, the reinstating cam connected with the lace cam so as to move therewith and adapted, when elevated, to be moved in line with the guide cam and in position to be engaged by the inactive drop-stitch needles whereby the latter are caused to be moved into operative position, and means to elevate the lace cam and the 85 deflecting cam.

5. In a knitting machine, the combination with the knitting cylinder and the tuck-stitch and drop-stitch needles, of the cam cylinder, the lace cam adapted when elevated, but not when depressed, to lift the tuck-stitch needles a distance sufficient to cause their latches to clear their loops, the stitch cam, cam devices adapted to disengage the drop-stitch needles from their loops and withdraw them from action, a reinstating cam adapted, when elevated, but not when depressed, to restore the needles thus rendered inactive into working position, means connecting said lace cam and reinstating cam and causing them to move in unison, and devices actuating said means, thereby reinstating the drop-stitch needles when the tuck-stitch needles operate as regular needles and causing the drop-stitch needles to remain out of action when the tuck-stitch needles are operating to form tuck stitching.

6. In a knitting machine, the combination with the knitting cylinder and the tuck-stitch and drop-stitch needles, of the cam cylinder, the lace cam adapted when elevated, but not when depressed, to lift the tuck-stitch needles a distance sufficient to cause their latches to clear their loops, the stitch cam, cam devices adapted to disengage the drop-stitch needles from their loops and withdraw them from action, a reinstating cam adapted, when elevated, but not when depressed, to restore the needles thus rendered inactive into working position, pins,

one secured to the lace cam and the other secured to both the lace cam and the reinstating cam, a third pin connected to one of the first mentioned pins, a spring normally upholding one of said pins thereby elevating the two last named cams, an arm, secured to the third pin, having a beveled face, and a lever adapted, when operated, to engage said beveled face and depress the third pin, there-

10 by depressing the two last-named cams.

7. In a knitting machine, the combination with the knitting cylinder and the tuck-stitch and drop-stitch needles, of the cam cylinder adapted when elevated, but not 15 when depressed, to lift the tuck-stitch needles a distance sufficient to cause their latches to clear their loops, the stitch cam, the clearing cam adapted to lift the drop-stitch needles to cause their latches to clear

their loops, the deflecting cam adapted when depressed to engage the drop-stitch needles and move them into inoperative position, a reinstating-cam adapted, when elevated, but not when depressed, to restore the inactive drop-stitch needles into working position, a pin connected with both the lace cam and reinstating cam, a pin connected to the deflecting cam, levers adapted to be actuated to positively actuate said pins respectively, pattern mechanism and devices actuated by the pattern mechanism to actuate said levers.

In testimony of which invention, I have hereunto set my hand, at Philadelphia, on this 20th day of July, 1906.

CHARLES A. SANTMYERS.
